UNITED STATES PATENT OFFICE

VOJTECH CIZEK, OF ASTORIA, NEW YORK

INTERNAL-COMBUSTION ENGINE

Application filed February 18, 1929. Serial No. 340,751.

The present invention relates to improvements in multiple-cylinder internal combustion engines, and more particularly to that type in which the cylinders are arranged in pairs. The invention pertains more specifically to four-cycle multiple cylinder engines in which a four-stroke cycle is carried out in each cylinder during a single revolution of the driven shaft of the engine.

10 One of the objects of the invention is to provide an engine of the type mentioned which is exceedingly simple in construction, efficient in operation, and which comprises a single shaft only, that is to say one in which 15 the cams for actuating the several valves of the engine are mounted on the main or driven shaft thereof.

Another object of the invention is to provide an improved driving connection between 20 the several working pistons of the engine and the driven shaft thereof, the novel feature residing in the fact that the connecting rods of the engine, while attached to the wrist pins of the pistons, are not directly attached to an 25 element carried by the driven shaft or to the latter, but co-operate with cams on said shaft.

With these and other objects in view, which will more fully appear as the nature of the invention is better understood, the same consists in the combination, arrangement and 30 construction of parts hereinafter described, pointed out in the appended claim and illustrated in the accompanying drawings, it being understood that many changes may be 35 made in the size and proportion of the several parts and details of construction within the scope of the appended claim, without departing from the spirit or sacrificing any of the advantages of the invention.

40 One of the many possible embodiments of the invention is illustrated in the accompanying drawings, in which:—

Figure 1 is a central vertical section taken through a pair of opposite cylinders of the 45 improved engine and the elements co-operating therewith; Fig. 2 is a section taken on line 2—2 of Fig. 1; and Figs. 3 to 6, inclusive, are diagrammatic views of the positions assumed by certain parts of the engine during the various intervals of one cycle.

In accordance with the invention one or more pairs of cylinders are employed, the cylinders of each pair being disposed on opposite sides of the driven shaft of the engine. With the pistons of each pair of cylinders is 55 associated an oscillatable bell-crank lever, to which are fixed the connecting rods co-operating with the said pistons. Each connecting rod bears against a cam, keyed or otherwise attached to a driven shaft, whereby the 60 reciprocating motion of the pistons is converted into rotary motion of said shaft. The several cams of the engine are so designed and arranged relative to each other that a four-stroke cycle is carried out in each cylinder during a single revolution of the engine shaft, without modifying the four-stroke cycle, that is to say a working stroke follows the ignition of the charge, followed by exhaust, charging and compression 65 strokes.

Referring now to the drawings, the numeral 10 indicates the crank-case of the engine, on which are mounted cylinders 11, the said cylinders being arranged in pairs and those of each pair being disposed on opposite sides of the driven shaft 12 of the engine. This shaft is journaled in the well-known manner in bearings 13, formed upon or carried by the crank-case. In each cylinder operates in the well-known manner a piston 14, the two pistons operating in a pair of cylinders being connected by connecting rods 15 and 15' with the opposite ends of a bell-crank lever 16, the latter being pivoted at 17 to the crank-case. The arms of the bell-crank lever are of equal 70 lengths, and the pivot pin 17 extends in parallel relation to the driven shaft 12 and is disposed in a vertical plane passing through the axis of the said shaft, as clearly shown in Figs. 1 and 2 of the drawings. On the pins 18 and 18', connecting the rods 15 and 15', respectively, with the bell-crank lever 16, are mounted rollers 19 and 19', respectively. In order to reduce friction between a roller and its pin, roller bearings 20 are used on these 75 elements. The two rollers 19 and 19', co-operating with a pair of pistons 14, are disposed on opposite sides of the respective bell-crank lever 16, as clearly shown in Fig. 2 of 80 100

the drawings. With each pair of rollers 19 and 19' cooperate two cams 21 and 21', keyed or otherwise fixed to the driven shaft 12, the said cams being located on opposite sides of the respective bell-crank lever 16.

5 Each pair of cams 21 and 21' is symmetrically disposed on the shaft 12, as clearly appears from Fig. 1 of the drawings. If divided on a circle into sections of 45 degrees, as indicated in Fig. 1 of the drawings, it will 10 be noted that the cam 21 has from the starting point 22 an uninterrupted curvature through the first 90 degrees in the direction of the arrow shown in Fig. 1 of the drawings. 15 In the next 45 degrees, its acting face is curved toward the longitudinal axis of the shaft 12, and thence through an arc of the next 45 degrees it is in the form of a sinusoidal curve to the point 23. From the point 23 back to the 20 point 22, that is to say through an arc of the next 180 degrees, the configuration of the cam is the same as that described in connection with the first 180 degrees. The configuration of the cam 21' is the same as that of the cam 21, but it is disposed in symmetrical relation to the latter on the shaft 12.

Each cylinder is provided with an inlet port and with an exhaust port, not shown as the construction of the same is well-known, 30 and these ports are controlled by inlet valves and outlet valves, which have not been shown in detail because their construction and operation is well understood by those versed in the art. In the drawings, however, the valve 35 operating mechanism has been illustrated, consisting of reciprocating members 24, associated with the inlet valves, and reciprocating members 25, co-operating with the exhaust valves. These reciprocating members act directly on the valve stems and 40 co-operate each with a bell-crank lever 26, pivoted at 27 to a bracket 28, the latter being mounted within the crank-case 10. One end of a bell-crank lever is in contact with the respective reciprocating element 24 or 25, while 45 its other end carries an anti-friction roller 29, acted upon by a cam 30 on the driven shaft 12. The arrangement is such that the inlet valves of a pair of cylinders is acted 50 upon by a single cam, and the outlet valves of a pair of cylinders is also operated by a single cam. In other words, the four-cylinder engine, as illustrated in the drawings, having four inlet and four outlet valves, comprises four cams only.

55 On the driven shaft is mounted a fly wheel 31, in the manner and for a purpose well-known.

The operation of the engine is as follows: 60 Referring to Fig. 2 of the drawings, let us assume that the cylinders are firing in the order I, II, III, and IV, attention being called to the fact that in the said figure the cylinders are not shown but the connecting 65 rods of the pistons and the elements co-oper-

ating therewith are delineated, so that the operation of the engine will be well understood by having reference to the said figure. The piston in cylinder I (Fig. 1) is at the end of its compression stroke and the piston 70 in cylinder II is at the end of its suction stroke. The explosion in the cylinder I, through the piston therein and the connection thereof with the shaft 12, imparts, as will be seen hereinafter, to the said shaft a 75 turn of 90 degrees in the direction opposite to that of the arrow shown in Fig. 1, carrying with it the several cams on the shaft and thereby imparting movement to the pistons in the remaining cylinders. Following now the action of the piston in the cylinder II and the movement of the cam 21 through a complete cycle of operation, it will be noted that during the first 90 degrees of a turn the charge in the cylinder II is compressed, the piston moving on its upward stroke so that the said cam and roller 19 at the completion of the upward stroke will occupy the positions shown in Fig. 4 of the drawings, they having moved from the positions shown in Fig. 3 of the drawings. When now an explosion occurs in cylinder II, all of the pistons of the engine move in directions opposite that in which they were moving during the first explosion, with the result that the crank-shaft moves 90 degrees in the direction opposite to that of the arrow shown in Fig. 1 of the drawings, whereby the cam 21 and roller 19 co-operating with the cylinder II are brought into the positions 90 shown in Fig. 5 of the drawings. Thereafter an explosion occurs in cylinder III, resulting in an exhaust stroke of the piston in cylinder II, the said piston moving during the next 90 degrees of shaft movement on its upward 95 stroke whereby its cam 21 and roller 19 are brought into positions shown in Fig. 6 of the drawings. When thereafter an explosion occurs in cylinder IV, it is obvious that during the next 90 degrees of shaft movement the 100 piston in cylinder II will move on its suction stroke, that is to say downwards, whereby its cam 21 and roller 19 are brought into the positions shown in Fig. 3 of the drawings. After this the cycle of operation is repeated. 105

Having now again reference to Figs. 3 to 6, inclusive, of the drawings, it will be noted that on each upward stroke of a piston the roller 19, co-operating with the cam associated with the said piston, swings in the direction of the movement of the cam, so that, while the cam moves through an arc of 90 degrees, the roller revolves along the cam surface through a distance of 45 degrees only, as will be seen by comparing Fig. 3 with 110 Fig. 4, or Fig. 5 with Fig. 6. On the other hand, when a piston moves on its downward stroke, the roller swings in a direction opposite to that of the movement of the cam, so that, while the cam moves through 115 120 125 130 135

an arc of 90 degrees, the roller moves along the surface of the cam through an angular distance of 135 degrees, as will be noted by comparing Fig. 4 with Fig. 5, or Fig. 6 with Fig. 3.

- 5 From the foregoing it appears that, when the pistons reciprocate in the well-known manner in the cylinders of the engine, the bell-crank levers 16 are caused to oscillate.
- 10 This oscillation is converted into rotation of the driven shaft 12 of the engine by the rollers, carried by the said bell-crank lever, and the cams 21 and 21', which are fixed, as above described, to the said driven shaft. It also
- 15 appears that in each cylinder of the engine a four-stroke cycle is carried out during a single complete revolution of the engine shaft, without modifying the four-stroke cycle.
- 20 It is obvious that, while herein a four-cylinder engine has been described, the number of cylinders may be increased or decreased according to the requirements without changing the principle of the invention.

25 What I claim is:—

An internal combustion engine including a driven shaft, a pair of cylinders arranged on opposite sides of said shaft, a piston in each cylinder, a bell-crank lever fulcrumed 30 in a vertical plane intersecting the longitudinal axis of said shaft, a connecting rod connecting each piston with said bell-crank lever, a roller on each connecting rod at its point of juncture with said bell-crank lever, 35 and two asymmetric cams symmetrically fixed to said driven shaft co-operating with said rollers, whereby the reciprocating motion of said pistons is converted into rotary motion of said shaft, said two cams being 40 located on opposite sides of said bell-crank lever.

Signed at New York city, in the county of New York, and State of New York, this 7th day of February, A. D. 1929.

45 VOJTECH CIZEK.
